UNITED STATES PATENT OFFICE.

WILLIAM JUDSON SMITH, OF ST. PAUL, MINNESOTA.

CAR HEATER.

Application filed May 8, 1920. Serial No. 379,729.

To all whom it may concern:

Be it known that I, WILLIAM JUDSON SMITH, a citizen of the United States, residing at St. Paul, in the county of Ramsey and State of Minnesota, have invented certain new and useful Improvements in Car Heaters, of which the following is a full, clear, and exact description, such as will enable others skilled in the art to which it 10 appertains to make and use the same.

This invention relates to heating devices, and with respect to some of its more specific features to hot air heating devices for railway vehicles.

15 One object is to provide an improved heating system of the class mentioned which is simple in construction and economical in first and operating costs, and which is easily installed on completely constructed cars, 20 either old or new.

Another object is to provide an improved hot air heating system for railway vehicles, and for other purposes, in which a particularly efficient circulation of the hot and cold 25 air in the system is effected.

Another object is to provide an improved heating system of the character mentioned in which practically the entire circulation of the air takes place within the compartment to be heated, the cold air being taken 30 into the heating system at points near the bottom of the compartment and the hot air discharged at points nearer the top thereof.

Another object is to provide an improved 35 heating system which utilizes a very high percentage of the heat produced by the combustion of the fuel used.

Other objects will be in part obvious and in part pointed out hereinafter.

40 The invention accordingly consists in the features of construction, combinations of elements and arrangement of parts which will be exemplified in the construction hereinafter set forth, and the scope of the application of which will be indicated in the following claims.

An illustrative embodiment of the invention is shown in the accompanying drawings wherein—

50 Figure 1 is a side elevation of a car embodying the invention, the side of the car being removed and certain parts shown in section more clearly to disclose the invention.

55 Fig. 2 is a horizontal section taken above

the floor line of the car and showing a plan view of the invention applied thereto, portions of the car floor being broken away to more clearly disclose details of the invention. 60

Fig. 3 is a transverse vertical section taken on line 3—3 of Fig. 2 looking in the direction of the arrow.

Fig. 4 is a transverse vertical section taken approximately on line 4—4 of Fig. 2 looking in the direction of the arrow. 65

Fig. 5 is a section through the car floor frame construction taken approximately on line 5—5 of Fig. 2, and showing a transverse vertical section through the heater. 70

Fig. 6 is a fragmentary transverse vertical section through the car taken immediately at the left of the heater, as shown in Fig. 2, and showing the latter in side elevation. 75

Fig. 7 is a fragmentary plan view of the heater.

Fig. 8 is a fragmentary side elevation of the hot air pipe leading from the end of the heater remote from the fire box. 80

The invention is shown in the drawing as embodied in a passenger car of the type usually employed on street railway lines. It is obvious, however, that it may be advantageously employed in connection with 85 freight cars or with other types of cars. It is particularly advantageous when employed in connection with fruit or vegetable cars, and with refrigerator cars when the same are used in cold weather for the shipment of 90 perishable goods, such as fruit, eggs and the like. In this connection it is noted that the feature particularly desirable is a heating system which will heat the space adjacent the floor line of the car to a temperature 95 which is suitable to protect the lading without at the same time raising the temperature too high at other parts of the car. The construction herein disclosed is particularly adapted to accomplish this function, as will 100 be obvious as the detailed description proceeds.

Referring now in detail to the embodiment shown in the drawing, the car body is indicated generally by the reference numeral 1. 105 The car is provided with side girders 2 having upper and lower stress members 3 and 4 shown in the form of angle bars having a vertical girder plate 5 riveted to the vertically disposed flanges of the angle bars. 110

Transverse underframe members shown as channel bars 7 are secured to the side girder members in any approved manner, and preferably extend from side to side of the car. 5 The floor 8 of the car may rest on the transverse floor frame members 7 or may be otherwise suitably supported in position thereabove.

Disposed beneath the floor of the car and 10 extending transversely thereof between two adjacent transverse floor frame members 7 is a stove or heater 9. This heater may be suitably supported from the adjacent floor frame members 7 as by supporting straps 10 15 of flat iron stock secured at their ends to said frame members 7 and extending under the stove to support the same in position. The floor may be of any approved construction and extending therebeneath over the heater 20 is a sheet 11 of heat insulating, heat resisting material, the purpose of which is to form a protection for the floor and the heater.

The heater may be constructed of any suitable material, but is preferably made of 25 sheet iron which may be covered on the exterior with suitable insulating heat resisting material 12. This insulating material may be magnesia or asbestos and is designed to keep the heat radiated from the heater down 30 to a minimum. A layer of muslin tape 13 may be placed over the insulating material as shown in Fig. 5 of the drawing. Near one side of the car and disposed at one end of the heater is the fire box or combustion 35 chamber 14. This fire box is suitably fitted with movable grate bars, ash-pit, ash retaining slide and other fire box elements. As the fire box construction and the elements in connection therewith are not 40 claimed herein, a detailed description of the same is considered unnecessary. The front of the fire box is supplied with a suitable door 16 hinged at its lower edge and adapted to cover an opening leading to 45 the fire box through which coal or fuel may be inserted. The fire box is disposed in a hot air chamber 15 lying between the fire box and the external walls of the heater. Lying within the extended portion of the 50 hot air chamber and extending from the fire box nearly to the opposite end of the heater is a smoke-pipe 18. This smoke-pipe forms a flue which is looped upon itself near the end of the hot air chamber as shown at 55 19 having a return portion 20 extending backwardly to a point near the fire box where it emerges from the hot air chamber as shown at 21. In the embodiment illustrated the looping of the smoke flue is accomplished 60 by means of a longitudinal dividing plate 22 secured in position in the center of the pipe as shown in Fig. 5 and fully described below. This looped construction in the smoke-pipe provides a large radiating surface in the hot air chamber. Through this

radiating surface the heat contained in the gases of combustion passing through the smoke-pipe is transmitted to the air in the hot air chamber, and thus the heat contained in said gases is effectively and efficiently 70 transmitted to the hot air chamber.

The smoke-pipe may be conveniently constructed and supported in the hot air chamber as shown particularly in Figs. 5 and 7 of the drawing. As there shown said pipe 75 is constructed of suitable sheet metal by bending a single sheet to form a comparatively large flue. In order to form both branches of the smoke-pipe a dividing plate 22 is secured in central position in the large 80 flue formed by bending the sheet metal plate. This dividing plate has flanged edges for securing same to the sheet metal walls, and extends from the fire box nearly to the opposite end of the flue, but terminates a short 85 distance from the end thereof so as to leave an opening as shown between the two branches of the flue. Both branches are supported in position in the hot air chamber by suitable flanged plates 24 secured to the 90 inner walls of the hot air chamber.

From the emerging portion 21, above referred to, the smoke-pipe extends laterally and upwardly through the car floor and runs horizontally closely above the floor of 95 the car as shown at 25 to a point near the end of the car where it passes into a vertical drum 26 turning upwardly therein and passing through the roof of the car as clearly shown in Fig. 1 of the drawing. At 100 the point where the smoke-pipe passes through the floor of the car a suitable aperture is provided, and this aperture may be supplied with a ring or lining of heat resisting material 25', which may be constructed of magnesia or any other suitable material. Apertures 27 may be formed near the base of the drum 26 in order that air may be taken into the drum and a draft created as the air therein is heated by the 110 smoke-pipe. It will thus be seen that the horizontally disposed portions of the smoke-pipe extends within the car compartment at a short distance above the floor thereof, and that the vertical portion of said pipe also 115 extends through the car compartment. The smoke-pipe thus acts as a radiator to radiate the heat contained in the gases of combustion and heat the interior of the car near the floor line, while the vertically disposed 120 portion of the pipe causes a current of hot air to be discharged from the drum 26 at a point remote from the floor line.

Air is taken into the hot air chamber of the heater through intake or cold air pipes 125 27 and 28 opening at their upper ends into the car compartment just above the floor line, and the lower ends opening into the lower portion of the hot air chamber. The upper openings of these pipes may be pro- 130

tected in any suitable manner, preferably by caps of an expanded metal mesh, not shown in the drawing.

In the embodiment shown in the drawing there are three hot air pipes extending from the hot air chamber to the interior of the car, so as to discharge the hot air at points remote from the floor and near the corners of the car. These hot air pipes as shown in the drawing also extend for a considerable distance longitudinally of the car and horizontally a short distance above the floor line thereof; by this disposition of the hot air pipes a very large radiating surface disposed close to the floor line is provided. One of these pipes as 29 extends from an outlet 30 at the upper portion of the hot air chamber near the fire box proceeding upwardly through a suitable aperture in the car floor and extending horizontally along the side of the car near the floor to a point near one corner of the car where it turns upwardly to a vertical portion 31 terminating at a point remote from the car floor in the upper part of the car compartment. The other hot air pipes 32 and 33 extend through an outlet 34 leading from the hot air chamber. This outlet is located at the end of the hot air chamber remote from the fire box and the pipes 32 and 33 are connected thereto and extend upwardly through the car floor into the car compartment. The adjacent ends of the pipes 32 and 33 may be made in the form of an integral unit as shown in Fig. 8 having a dividing partition 32' for dividing the opening in the pipe 32 from that in pipe 33. This integral unit is fitted with an angularly disposed portion 34' which is adapted to telescope with the outlet 34. Both of these pipes extend horizontally above the floor near the car side and terminate in vertical portions 35 and 36 at opposite corners longitudinally of the car, so as to discharge the hot air at points remote from the floor, as described above in connection with the hot air pipe 29.

The arrangement of the smoke pipe and hot air pipes within the car compartment close to the floor thereof as above set forth provides a great radiating surface radiating heat low down in the car compartment. This arrangement effectively heats the lower portion of the compartment without unduly raising the temperature of the upper portion thereof. On account of the great radiating surface a large percentage of the heat of the hot air or gases is conducted through the walls of the pipes and radiated from the surfaces thereof before the air is discharged from the open ends of the pipes. As shown in Fig. 3 the hot air pipes may be supported above the car floor on suitable supports 37 which may be of any suitable heat resisting and insulating material. A box 38 for fuel having doors 39 may be conveniently mount-

ed under the car floor and suspended in position from the transverse floor frame members 7.

In the embodiment illustrated wherein the invention is installed in a street passenger car, the smoke-pipe and hot air pipes may be conveniently disposed below the car seats 41 and 42. As shown in Fig. 4 a protecting plate 38' may be placed above the smoke-pipe 25 and an expanded metal mesh placed below the front edge of the seat. By this construction the hot air is directed towards the front of the seat and is prevented from passing directly upwardly through the seat bottom.

In the construction provided by this invention the heat circulation takes place wholly within the car, the heater, and pipes passing therebetween, and the entire volume of air within the car is thus reheated at comparatively short intervals of time. Actual tests made on installations of this type of heating system by measuring the velocity of air in the return or cold air pipes, have shown that the amount of air being reheated every hour is equal to three times the cubical contents of the car.

It will be further noted that the construction herein provided accomplishes an efficient heating of the car and maintains a comparatively uniform temperature throughout the car compartment. Also a particularly advantageous feature resides in this construction, as all moving parts, such as fans or other circulating means, are entirely avoided. There is no possibility of freezing and consequent damaging the pipes and connections as is the case where hot water or steam heaters are employed. On account of the simple nature of this heating system, it is easily and cheaply installed on cars of standard design, either when the car is being built, or on old cars.

The description of the operation of this invention is fully embodied in the above detailed disclosure, and no reiteration is believed to be necessary to a clear understanding thereof by any one skilled in the art.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I

claim as new and desire to secure by Letters Patent is:

1. In a car heating system, in combination, a car compartment, a heater disposed transversely of the car intermediate the ends thereof and below the floor of said compartment, said heater having a fire box disposed adjacent to one side of the car, and a hot air chamber extending laterally therefrom toward the opposite side of the car, hot air ducts connected to said heater at opposite ends thereof and positioned to conduct hot air from said hot air chamber and to discharge it near opposite ends of the car compartment in the upper portion thereof, cold air ducts extending from said heater and communicating with said hot air chamber in the vicinity of said fire box, and also communicating with the interior of said compartment near the floor thereof for receiving air from said compartment and conducting it to the hot air chamber, and a smoke pipe extending from said fire box into said compartment and being in position to radiate heat therein remote from the receiving ends of said cold air ducts and from the points of discharge of said hot air ducts, whereby distribution of heat at opposite ends of the car is equalized.
2. In a car heating system, in combination, a car compartment, a heater disposed transversely of the car intermediate the ends thereof and below the floor of said compartment, said heater having a fire box disposed adjacent to one side of the car and a hot air chamber extending laterally therefrom toward the opposite side of the car, hot air ducts connected to said heater at opposite ends thereof and being positioned to conduct hot air from said hot air chamber and to discharge it near opposite ends of the car compartment in the upper portion thereof, cold air ducts extending from said heater and communicating with said hot air chamber in the vicinity of said fire box, and also communicating with the interior of said compartment near the floor thereof for receiving air from said compartment and conducting it to the hot air chamber, and a smoke pipe connected to said fire box and having a divided section disposed in said hot air chamber for conducting the hot gases of combustion in reverse directions therein for providing large radiating surface, said smoke pipe also extending from said heater into the car compartment, and being disposed to radiate heat therein at a part spaced from the points of discharge of said hot air ducts so as to equalize the distribution of heat at opposite ends of the car compartment.
3. In a car heating system, in combination, a car compartment, a heater disposed transversely of the car intermediate the ends thereof and below the floor of said compartment, said heater having a fire box disposed adjacent to one side of the car and a hot air chamber extending laterally therefrom toward the opposite side of the car, hot air ducts connected to said heater at opposite ends thereof and being positioned to conduct hot air from said hot air chamber and to discharge it near opposite ends of the car compartment in the upper portion thereof, and cold air ducts extending from said heater and communicating with said hot air chamber in the vicinity of said fire box, and also communicating with the interior of said compartment near the floor thereof for conducting the air from said compartment to the hot air chamber.
4. In a car heating system, in combination, a car compartment, a heater disposed transversely of the car and below the floor of said compartment said heater having terminal portions lying adjacent opposite sides of the car and including a fire box adjacent to one side of the car and a hot air chamber extending laterally therefrom across the car, hot air ducts extending from opposite ends of said heater and being disposed at opposite sides of the car for conducting hot air to one end of the car compartment and for discharging it in the upper region thereof, and a hot air duct and a smoke pipe extending respectively from opposite ends of said heater and extending along opposite sides of the car for distributing heat at the opposite end of said car compartment.

In testimony whereof I affix my signature, in the presence of two witnesses.

WILLIAM JUDSON SMITH.
